UNITED STATES PATENT OFFICE.

ALBERT O. PRICE, OF COSHOCTON, OHIO.

DESIGN FOR A RADIO CABINET.

Application filed May 6, 1924. Serial No. 9,491. Term of patent 14 years.

To all whom it may concern:

Be it known that I, ALBERT O. PRICE, a citizen of the United States of America, residing in the city of Coshocton, county of Coshocton, and State of Ohio, have invented a new, original, and ornamental Design for Radio Cabinets, of which the following is a specification, reference being

had to the accompanying drawing, forming part thereof.

The figure is a perspective view of the radio cabinet showing my new design.

I claim:

The ornamental design for a radio cabinet as shown.

ALBERT O. PRICE. [L. S.]
